SLIPPER SOCK

John H. Bodorff, Rockford, Ill., assignor to Rockford Textile Mills, Inc., Rockford, Ill., a corporation of Illinois

Application April 6, 1951, Serial No. 14,739

Term of patent 14 years

(Cl. D47—7)

To all whom it may concern:

Be it known that I, John H. Bodorff, a citizen of the United States, residing at Rockford, in the county of Winnebago and State of Illinois, have invented a new, original, and ornamental Design for a Slipper Sock, of which the following is a specification, reference being had to the accompanying drawings, forming a part thereof.

In the drawings:

Figure 1 is a front perspective view of the slipper sock showing my new design.

Fig. 2 is a fragmentary plan view of the toe portion of the same.

The design is especially characterized by the use of a covering of segmental shape over the toe of the sock and perforated by a series of holes arranged in a manner as illustrated on the drawings.

I claim:

The ornamental design for a slipper sock, substantially as shown and described.

JOHN H. BODORFF.
